UNITED STATES PATENT OFFICE.

JOHN LINES, OF WATERBURY, CONNECTICUT, ASSIGNOR TO THE SCOVILL MANUFACTURING COMPANY, OF SAME PLACE.

DESIGN FOR A TIRE-VALVE CAP.

SPECIFICATION forming part of Design No. 28,585, dated May 10, 1898.

Application filed October 18, 1897. Serial No. 655,640. Term of patent 7 years.

all whom it may concern:

Be it known that I, JOHN LINES, of Waterbury, in the county of New Haven and State of Connecticut, have invented a new Design for a Tire-Valve Cap, (Case B;) and I do hereby declare the following, when taken in connection with the accompanying drawing and the letters of reference marked thereon, be a full, clear, and exact description of the same, and which said drawing constitutes part of this specification and represents a side view of a tire-valve cap embodying my design. This invention relates to a design for tire-valve caps; and the design consists in the form of the cap, as hereinafter described, and shown in the accompanying illustration. As herein shown, the tire-valve cap is characterized by having its cylindrical body A

surrounded below its upper edge by a knurled band B, by having a post C project upward from the center of the said top, and by having the surface of said post merge into said top, so as to form a curved line from the top of said post to the extreme outer edge of the top of the cap, all as shown in the accompanying illustration.

I claim—

The design for a tire-valve cap as herein shown and described.

In testimony whereof I have signed this specification in the presence of two subscribing witnesses.

JOHN LINES.
